17 Claims. (Cl. 178—7.1)

The present invention relates to a method of scanning for television and like systems.

To impart the necessary scanning motion to a beam of light it is known to employ moving optical parts, such as mirror drums, Nipkow discs and the like. These methods necessitate the use of at least one component moving at a very high speed to accomplish the high speed component of scanning, and furthermore the line frequency of the scanning cannot be easily altered. Other scanning methods avoid these disadvantages by employing a moving electron beam, but with these methods high electrical voltages are necessary; and the operation must take place in a vacuum. It is also known to employ the Kerr effect to oscillate the extraordinary ray which results from double refraction, but the resulting movement is small.

One object of the present invention is to provide an improved method of scanning which avoids the use of high speed moving parts.

Another object of the invention is to provide a scanning method in which the line scanning frequency can be easily changed at will.

A further object of the invention is to provide a scanning method in which the synchronisation difficulties associated with normal methods are avoided.

The invention will now be described by way of example with reference to the accompanying drawings in which Figs. 1 and 2 illustrate the action of a well known form of light modulating cell; Fig. 3 illustrates a television receiver embodying the present invention; Fig. 4 is the circuit diagram of an amplifier and shaping circuit for the line synchronising impulses; Figs. 5 to 7 are explanatory diagrams; Figs. 8 and 9 illustrate an alternative form of television receiver; Fig. 10 is an explanatory diagram; Figs. 11 and 12 illustrate a modified form of the receiver illustrated in Fig. 8; Fig. 13 shows a method of increasing the member of interference images by using several wave trains in one cell; Figs. 14 and 15 illustrate in plan and side elevation respectively a further form of television receiver employing the present invention; Figs. 16 and 17 illustrate in plan and side elevation respectively a film transmitter embodying the present invention; Fig. 18 illustrates a direct viewing television transmitter embodying the present invention; and Fig. 19 illustrates the method of producing low speed scanning with aid of the present invention.

Referring to Fig. 1, an image of a light source 1 in the form of an illuminated slot is focussed in the plane 2 by means of lenses 3. Between the

lenses is placed a transparent cell 4, filled with a liquid 5. At one end of the cell is situated a piezo-electric crystal 6 which is set into vibration by high frequency alternating electrical energy applied via terminals 7 to electrodes 8. Travelling compressional waves are thus produced in the liquid and their effect is such that in addition to the normal or central image of the slot 1 in the plane 2, there is produced a series of side images, or interference fringes. In Fig. 2 is shown the central image 9, and the side images 10 thus produced by optical interference. As the amplitude of the liquid waves increases, the central image becomes weaker and the side images become brighter. If the central image is obscured by means of a stop 11, and the light from the side images is collected by a lens 12 on to a screen 13, the intensity of the light on this screen will vary in accordance with the amplitude of the liquid waves. Obviously the same result will be obtained by obscuring the side images and utilizing the light from the central image. The lens 12 is arranged to focus an image of the liquid surface on to the screen 13, so that each point on the liquid surface, e. g., the point 14 and 15, will be separately imaged on the screen, e. g., at 16 and 17, the intensity of each image depending upon the amplitude of the waves at the corresponding point in the cell. If the high frequency potentials applied to the crystal are modulated with television signals, then the amplitude of the travelling waves will vary from point to point along the length of the cell in accordance with the amplitude of the television signals, i. e., in accordance with the brightness of a series of adjacent picture points lying in a picture line. Hence on the screen 13 there will be obtained a series of moving images of these picture elements which can be utilized to reconstitute the picture. Hitherto this has been accomplished by replacing the screen 13 with a high speed scanning member, such as a rotating mirror drum, which imparts to the images of the picture elements a motion in the opposite direction to their own motion so that they are immobilized on the viewing screen. The above described cell, and method of utilizing it for television purposes are more fully described in the specification of J. H. Jeffree's application Serial No. 8541/35.

Methods of utilizing these cells for television receivers according to the present invention will now be described with reference to Figs. 3 to 7.

A beam of light from a source 20 passes through a Kerr cell, shown diagrammatically at 21 which acts in known manner to modulate the intensity 55

- of the light in accordance with the picture signals, and then through a cell 22 of the type illustrated in Fig. 1. The cell provides the high speed component of scanning in a manner to be described.
- 5 The mirror drum 26 rotates at a slow speed, and sweeps the light beam over the screen in a direction at right angles to the plane of the paper, to provide the low speed scanning component. The television signals received on the receiver 27
- 10 are applied to the filter 28 which separates the picture signals from the line synchronizing impulses, the former being fed to the Kerr cell, and the latter being fed through a shaping circuit and amplifier 29, to be described later, to the modulator 30 where they modulate high frequency oscillations from the source 31. The modulator is biased so that normally the high frequency oscillations are reduced to a very low value, the action of each synchronizing impulse being to permit the generation of a short group of oscillations (Fig. 6). The output of the modulator is fed via terminals 32 to the crystal of the cell 22, short discontinuous groups of waves being generated in the liquid of the cell.
- 15 25 A description of the amplifier and shaping circuit 29 will now be given with reference to Figs. 4 and 5. The circuit comprises three valves V₁, V₂ and V₃ with resistance-capacity coupling between them. The line synchronizing impulses applied to the grid of valve V₁ will have the form illustrated in curve I of Fig. 5. The anode circuit of this valve contains a resistance 33 and a condenser 32 in parallel. Each of the square-topped impulses will charge the condenser 32, which will then discharge through the resistance 33. By suitably choosing the time constant of the circuit 32, 33 and also the relative values of the condenser 32 and resistance 33, the charging time is made equal to the discharging time so that the signals applied to the grid of valve V₂ will have the triangular shape illustrated in curve II of Fig. 5. The grid of this valve has applied thereto a negative bias, the value of which is regulated by the variable resistance 34. This bias can be regulated so that the valve V₂ transmits only the upper portion of the triangular shape impulses; for example, the portion above the dotted line in curve II of Fig. 5. Hence, the impulses applied to the grid of valve V₃ will have the shape illustrated in curve III of Fig. 5. Valve V₃ acts as an amplifier, the shape of the impulses in its output circuit being illustrated in curve IV of Fig. 5. Hence, by varying the value of resistance 34 and hence the position of the dotted line 55 in curve II of Fig. 5, the ratio of the space occupied by an impulse to the distance between two impulses can be varied, this ratio becoming smaller as the negative bias on the grid of valve V₂ is increased.
- 60 In Fig. 6 is illustrated the high frequency wave applied to the crystal of cell 22. It is seen that the normal amplitude of the wave is so small as to be negligible, the amplitude increasing very greatly each time an impulse is applied to the modulating circuit 30.
- 65 Each group of waves generated in the liquid of the cell 22 will produce an interference pattern, the central image of which is obscured by the stop 23, the light from the side images being collected by the lens 24 and focussed on the screen 25. There will thus be formed on the screen 25 a spot of light, the size of which will depend upon the length of the group of waves in the liquid. This spot of light will move across the screen at a speed depending upon the rate of

travel of the group of waves through the liquid of the cell. Hence the cell 22 acts in a manner similar to that of an opaque screen with a slot in it, the slot moving in a direction parallel to the axis of the mirror drum 26. Thus elemental areas of the screen corresponding to the original picture elements will be momentarily illuminated. A cell operated to produce this effect will be hereinafter referred to as a "wave-slot" cell. The frequency of the high frequency oscillations derived from the source 31 is so chosen with relation to the liquid in the cell 22, that one group of waves is leaving the crystal at the instant that the preceding group of waves has reached the top end of the cell 22. Also the value of the resistance 33 is adjusted until the ratio of the length of a wave group to the length of the cell is equal to the ratio of the length of a picture element to the length of the picture line. The former ratio determines the degree of "definition" of which the receiver is capable. The latter ratio is the "definition" of the transmitter. In Fig. 7 in which the rectangle 36 denotes the boundary of the cell or of that part of it that is active in influencing the light passing through it, the waves being propagated from one end of the rectangle to the other. The curve 35 represents the amplitude of the waves at different points along the cell at an instant of time, the portion 37 indicating the sudden increase in amplitude 30 due to the arrival of an impulse. The ratio of the width of the portion 37 to the length of the rectangle 35 is the definition of the receiver. It will be understood that there is no advantage in making the "definition" of the receiver higher 35 than that of the transmitter. The best result is attained by the adjustment described above.

If it is desired to employ the light from the central image and to obscure the side images, as described above, then the modulator 30 must be 40 biased to such an extent that unmodulated oscillations from the terminals 31 is applied to the crystal with full amplitude, the impulses being applied to the modulator in such a sense that they momentarily quench the oscillation. The 45 output from the modulator will thus be represented by a curve which is the inverse of that shown in Fig. 6.

Under these conditions the wave slot cell 22 and the mirror drum 26 cooperate to provide respectively the high and low speed scanning components, and since the light incident upon the screen 25 is modulated with the picture currents by the Kerr cell 21, the picture will be reconstructed.

The apparatus shown in Fig. 3 can be operated in an alternative manner to that described above to produce the same effect. This is done simply by applying the shaped line synchronizing impulses existing in the output circuit of the device 60 29 to the terminals of the Kerr cell in place of the picture currents and applying the latter to the input of the modulator 30. The amplitude of the waves in the cell will now vary along the length of the cell in accordance with amplitude 65 of successive picture elements, and since the length of the cell corresponds to the length of the picture line, there will be represented in the cell at successive instants of time a complete picture line. A cell operated in this manner 70 will hereinafter be referred to as a modulator cell. The picture line will be imaged on the screen 25 exactly as before, but owing to the fact that the waves are travelling through the liquid, the corresponding images will be travelling 75

across the screen instead of remaining stationary, and hence cannot be observed. This is rectified by the action of the Kerr cell, which cannot transmit light in the absence of electrical impulses applied to it. Since these impulses occur only at line frequency, and since their duration time is only that of one picture element (due to the previously described action of the circuit 29), the Kerr cell will act as a shutter and the cell 22 5 will be intermittently illuminated at line frequency, so that each picture line is momentarily projected on the screen 25, and no motion of the line can be discerned, since the time of each illumination period is of the order of one picture 10 element. Due to the action of the mirror drum 26, each line will be momentarily projected below the previous line to reconstitute the complete picture. In this case it is clear that a time limitation is imposed upon the light passing through 15 the cell in contradistinction to the first method of operation, in which a space limitation was imposed upon the light. The shorter the period of illumination is made, the higher the definition becomes. In practice the result is satisfactory 20 if the duration of each flash of light to the time between two flashes approximates to the ratio between the length of a picture element to the 25 length of the picture line.

It is clear that the light efficiency of the apparatus illustrated in Fig. 3 when operated in accordance with this second method will be very poor, since the greater portion of the light emitted by the source 20 is wasted. This can be improved by utilizing a discharge tube, such as a 30 high-pressure mercury vapour lamp, which lights intermittently at the line frequency instead of continuously, the current consumed and hence the brilliancy being very great at each flash. The Kerr cell or an equivalent shutter controlled 35 by the line synchronizing impulses, then limits the duration time of each flash to the order of that of one picture element. The waste of light can be avoided still further by dispensing with the Kerr cell and employing a lamp which can light intermittently at a frequency in the neighbourhood of line frequency, but in which the duration of each period of illumination persists only for a time of the order of the duration time 40 of a picture element, the lamp being controlled 45 by the shaped line synchronizing impulses. Suitable for this purpose are stroboscopic lamps such as described in the article entitled "A cold cathode arc-discharge tube" in "Electrical Engineering", volume 55, No. 7, pages 799, etc.

50 A form of receiver employing a wave-slot cell and a modulator cell is shown in Fig. 8. Light from a source in the form of an illuminated slit 40 is passed through the modulator cell 41, to the terminals 42 of which is applied a high frequency 55 oscillation modulated with the picture currents. The slotted screen 43 obscures the central image, the two slots 44 permitting light from the side images to pass through lens 45 to a wave slot cell 46, the lens 45 focussing an image of the liquid 60 of cell 41 on to the liquid of cell 46. The terminals 47 of this cell are fed with a high frequency oscillation modulated with the shaped line synchronizing impulses, as described in connection 65 with Fig. 3. The slotted screen 48 is designed 70 to permit the passage of light only from the side images produced by the wave slot in the wave slot cell. Since the slots 44 of the screen 43 each act as a modulated light source, the cell 46 will produce two overlapping sets of interference images, 75 and hence the screen 48 is provided with two stops

49 for obscuring the two central images, and slots 50 for permitting the passage of light from the side images. The two screens 43 and 48 are illustrated more clearly in Fig. 9. The lens 51 forms an image of the liquid of the cell 46 on the viewing screen 52, the low speed scanner 53 sweeping this image over the the screen in a direction at right angles to the paper.

Referring now to Fig. 10 in which the rectangle represents the wave slot cell 46 it is seen that an 10 image of the picture modulated waves of the cell 41, represented by the full curve 54, moves across the cell in the direction of the upper arrow, whilst the wave slot itself, produced by the impulses applied to the terminals 41, and represented by 15 the dotted curve 55, moves at the same speed in the direction of the lower arrow, the relative motion between the two producing the required 20 high speed scanning component. It is clear that exactly the same result will be obtained by interchanging the modulator and wave slot cells, in 25 which case an image of the wave slot is projected on to the surface of the modulator cell. It is preferable, though not essential, that the two sets of waves should move parallel to one another in 30 opposite directions as shown in Fig. 10. Thus they may move in the same directions at different speeds, or alternatively one set of waves may be at an angle, for example 45°, to the other set. In the latter case, the resulting picture line would 35 be at an angle to that normally obtained but this could be corrected by a suitable turning of the two cells with respect to the remainder of the apparatus.

In the arrangement of Fig. 8 it can be arranged 35 that the wave slot 55 moves with a greater speed than the picture modulation 54, so that the time during which the wave slot is active is small compared with the duration time of a picture line. In this case, for a given degree of picture definition, the width of the wave slot, and therefore 40 the resulting illumination can now be increased. The light source can be arranged to light intermittently and only during the time when the wave slot is active, thereby affecting a saving of 45 the energy required to produce the light. The line synchronizing impulses are used to control both the wave slot cell and the light source. Alternatively a "Kerr" cell or equivalent shutter 50 may be used with a constant light source, thereby avoiding the incidence of unwanted stray beams of light during the time when the wave slot is inactive.

An important and useful feature of the receiving arrangements described above is that a stationary picture will be reproduced even when the line scanning frequency at the transmitter alters. Thus, considering Fig. 8, if at the transmitter the line scanning frequency suddenly increases, the length of a picture line as represented by the 60 picture modulations in the cell 41 will decrease, but this is compensated by the fact that the frequency of the synchronizing impulses applied to the cell 46 will increase, and hence the distance 65 between two successive wave slots will also decrease in the same proportion. Hence, on the screen the reproduced picture will simply contract in the direction of the scanning lines but will otherwise remain stationary. It is thus clear 70 that the problems of synchronization present in known forms of receiver do not exist in the present case.

In Fig. 11 is shown a modification of the receiver Fig. 8, in which the two cells 41 and 46 are replaced by a single cell 63. The light source 75

60 is a filament lamp provided with a plurality of filaments side by side to provide a source of light having a more or less square shape. The cylindrical lens 62 forms an image of the filament in the liquid of the cell 63 in one plane, whilst in the plane at right angles, the light diverges from the slot 61 to illuminate the face of the cell 63. The lenses of the cell 63 form an image of this slot upon the central opaque portion of the screen 66. The cell 63 contains two crystals 64, 65, situated one above the other. To the crystal 64 is applied an oscillation modulated with the picture currents, so that the upper part of the cell acts as a modulator cell and corresponds to the cell 41 of Fig. 8. The light from the side images passes through the slots of the screen 66, is reflected by the prism 67 through the lens 68 to the lower part of the cell, which acts as a wave slot cell and corresponds to the cell 46 of Fig. 8, the line synchronizing impulses being applied as modulations of a high frequency oscillation to the crystal 65. The lens 68 forms an image of the upper part of the liquid surface in the cell 63 upon the lower part of the liquid surface, and corresponds to lens 45 of Fig. 8. Also the cylindrical lenses of the cell 63 form images of the slots in the screen 66 upon the two opaque portions of the screen 70, the light being reflected by means of the mirror 69. Hence, a second interference pattern is produced on the screen 70, the central images being obscured, and the light from the side images passing through the three slots via the cylindrical lens 71, 73 and the mirror drum 72 to the screen 74. The operation of this receiver is substantially similar to that illustrated in Fig. 8 and need not be described in detail. The screen 66, prism 67 and lens 68 may be replaced by the two dotted portions 75 cut from a spherical concave mirror as illustrated in Fig. 12.

The receivers described above have one disadvantage, namely that the quantity of light which can be utilized is somewhat small. Thus in Fig. 8 the lenses 45 and 51 cannot work at their maximum aperture. It is possible, however, to utilize the full aperture of these lenses by working with several sets of interference images side by side instead of one set of interference images. One method of accomplishing this is illustrated in Fig. 13. In this figure there is shown a light source 76 and cell 78 and two slotted screens 77 and 82, these elements corresponding to the light source, modulator cell and slotted screens shown on the left side of Fig. 8. The light source is very large in the plane of the paper and can be constituted by a long filament lamp as shown. The screen 77 contains a number of slots each of which acts as a separate light source. The lenses 79 of the cell focus images of these slots on the screen 82 in such a way that the image of each slot is formed on the opaque portion lying between two slots of the screen 82. The cell contains a number of crystals 80 equal in number to the number of slots in the screen 77. For the sake of simplicity only three crystals are shown in the drawings. The crystals are connected in parallel to terminals 81, a suitable high frequency oscillation modulated with the picture currents being applied to these terminals. The crystals are so arranged that each produces a train of waves in different direction, the direction of the waves being indicated by the arrows 86, 87 and 88. With this arrangement, each wave train will influence only the beam of light which passes at right angles to it; thus the wave train 86 will

influence the beam of light 83 coming from the middle slot, whilst the wave trains 87 and 88 will influence respectively the light beams 84 and 85 coming from the extreme slots of the screen 77. There will thus be formed in the screen 82 a number of sets of interference images, each corresponding to one of the light beams issuing from the slots in the screen 77. The central image of each of these sets is obscured by the screen 82 and the light from the side images of all the sets passes through the slots in the screen 82 and is utilized in a manner similar to that described in Fig. 8. It is clear that the remainder of the apparatus will be similar to that shown in Fig. 8, the cell 47 being replaced by a second cell similar to cell 78 of Fig. 13 and the screen 48 of Fig. 8 being replaced by a screen with a larger number of apertures and corresponding to the screen 82. With this arrangement the lenses 45 and 51 in Fig. 8 can be used at their full aperture with a corresponding increase in the amount of light which can be utilized.

In Figs. 14 and 15 is shown an alternative method of increasing the light handling capacity of a receiver. These figures show in plan and side elevation respectively a television receiver employing one cell 91 which acts as a wave slot cell, the light incident upon the cell being modulated in any suitable manner will be in accordance with the picture currents. This particular arrangement is chosen for illustration in view of its simplicity, and it will be clear that the arrangement can be adapted to any of the receiving methods illustrated with reference to Figs. 3 to 11. To further simplify Fig. 15, the light rays are shown as being transmitted through the reflecting surfaces 93, 95 instead of being reflected by them. The light source 90 in this case has a large size in the plane at right angles to the plane containing the waves in the cell 91; i. e., its large dimension is at right angles to the large dimension of the light source of Fig. 13. In the plane of Fig. 15 the cylindrical lens 92 forms an image of the light source 90 in the liquid of the cell 91. In the plane of Fig. 14 the lenses of the cell 91 form an image of the light source 90 on the surface of three mirrors 95, each of these mirrors being provided with an opaque strip. The light emerging from the cell 91 is reflected on to the mirrors 95 by a set of three mirrors 93, which are situated one above the other in the plane of Fig. 15, and are inclined relatively to one another about the axis 94 as shown in Fig. 14. Each of these mirrors will reflect in a different direction the light from one third of the image of the light source in the liquid, this being due to their relative displacement about the axis 94. The top and bottom mirrors of the mirrors 93 are also tilted about their own longitudinal axis as shown in Fig. 15, the effect being that the three portions of the light source image are now brought into line side by side. These three portions are focussed in the plane of Fig. 14 on the surface of three mirrors 95, these three mirrors also being displaced about the axis 96 which is at right angles to the axis 94. The light from each one third portion of the light source image will produce its own interference pattern in the plane of the axis 96, the central images of these three patterns being obscured by the opaque strips on the mirrors 95. The light from the side images is collected by the lens 97 which focusses an image of the liquid surface on the screen 99 via the low speed mirror drum 98. Owing to the fact that the light incident upon the mirrors 95 is coming from different heights 75

in the plane of Fig. 15, it would also be reflected at different heights if a plane mirror were used in place of the mirrors 95. This is corrected by the angular displacement of the mirrors 95 about the axis 96. The function of the two sets of mirrors is to transform the incident beam, which has its large aperture in the plane containing the direction of motion of the low speed scanner (i. e., the plane of Fig. 15) into a beam having its large aperture in the plane containing the direction at right angles to the low speed scanning direction (i. e., the plane of Fig. 14) since it is only in this plane that the large aperture can be fully utilized. In order to achieve this it is possible to utilize any of the beam transforming devices described in the specification of J. H. Jeffree's application Serial No. 3062/35 in place of the two sets of mirrors described above. A still further increase in the light can be obtained by combining the methods illustrated in Fig. 13 with the methods illustrated in Figs. 14 to 15, since a light source can then be used which is large in both dimensions.

If the optical arrangements of Figs. 14 and 15 are employed in conjunction with a small light source, then the size of the low speed scanning member can be made very small in the direction of scanning, i. e., in the plane of Fig. 14. There is no difficulty in making the size of this member small in the non-scanning direction, i. e., in the plane of Fig. 15 so that as a result a very small low-speed scanner can be used. This makes it possible to use for this purpose an oscilloscope with a very small mirror, the oscilloscope being driven with currents having a saw-toothed wave form and generated by any well known time base circuit controlled by the picture frequency synchronizing impulses. In addition to the many obvious advantages, such an oscilloscope has the advantage that its amplitude of vibration becomes, or can be made to become, less as the scanning frequency radiated from the transmitter increases. It has already been pointed out that such an increase will produce a lateral contraction of the received picture when the present invention is employed, and due to this decrease in amplitude of the oscilloscope, a corresponding vertical contraction can be automatically obtained, thus preserving the original picture ratio.

It must be emphasized that the use of such a small low speed scanner, and in fact, any of the arrangements described with reference to Figs. 13 to 15, only become possible when the present invention is employed. If an attempt were made to employ them with a system using a normal high speed scanning member the size of this member would have to be increased to such a size as to be impracticable in order to obtain the necessary light handling capacity.

The application of the invention to a television transmitter will now be described. In Figs. 16 and 17 there is shown in plan and side elevation respectively a television transmitter for cinematograph films. A light source 100 illuminates a slot 101, the cylindrical lens 102 forming an image of the light source in the liquid of a wave slot cell 103, whilst the lenses 104 of the cell form an image of the slot 101 on the screen 107. The cylindrical lens 108 forms an image of the liquid of the cell upon the slot 110 whilst the cylindrical lens 109 forms an image of the liquid and of the light source image focussed therin upon the slot 110. The spherical lens 111 forms an image of the slot 110 upon the film 112 to be scanned,

which film moves in the direction of the arrow. A suitable source of high frequency electrical oscillations is modulated with impulses generated in any well known manner and shaped by means of the circuit illustrated in Fig. 4, the modulation being effected in such a manner that the final output can be represented by the curve shown in Fig. 6. This output is applied to the terminals 106 of the crystal 105 and consequently, in the manner already described, a spot of light is caused to traverse the film 112 in the direction of its width to provide the high speed component of scanning, the low speed component being provided by the movement of the film in the direction of the arrow. The light transmitted through the film falls on the photo cell 113 which is connected to suitable transmitting apparatus 114. The size of the scanning spot, and hence the definition, can be regulated within very wide limits by adjusting the width of the slit 110, which limits the size of the spot in one direction, and by adjusting the resistances 34 of Fig. 4 which limits the size of the spot in the other direction. Also the scanning frequency can be very easily altered by varying the frequency of the impulse generator and the speed of movement of the film. By suitably choosing the frequency of the impulses in relation to the speed of movement of the film, normal or interlaced scanning can be produced at will.

In Fig. 18 is illustrated a direct viewing transmitter employing the present invention. The lens 116 forms an image of the object 115 upon the surface of the screen 118, this image being swept over the screen by the mirror 117 of a low speed oscilloscope which is driven by saw-toothed oscillations derived from a suitable time base circuit at the desired picture frequency. The screen 118 contains a long slot 119, the image of the object being exposed through the slot, line by line, as it is swept over the screen. The light from each picture line is transmitted through a slotted screen 120 and a cylindrical lens 121 to a wave slot cell 122, the lens 121 forming an image of the slot 119 in the liquid of the cell. The screen 120 is provided with a number of slots each of which acts as a virtual light source, and the lenses of the cell 122 image these slots upon the slotted screen 123 in such a way that the images fall between the slots of the screen 123. The cell 122 is provided with a number of crystals fed in parallel through the terminals 125, the number of crystals being equal to the number of slots in the screen 120. The cell and the associated screens 120 and 123 are the same as those illustrated in Fig. 13 and operate in an identical manner. Consequently the light transmitted through each slot of the screen 123 will be the light from the side images of an interference pattern corresponding to one of the slots of the screen 120. Hence the total light emerging from these slots will be modulated with the light values of successive picture points. This light is incident upon the photo cell 124, the output of which is transmitted via terminals 126 through a suitable transmitting apparatus.

The low speed component of scanning can also be produced by a combination of two wave slot cells, instead of by the mechanical means hitherto described. An arrangement for producing this is shown in Fig. 19, which shows in diagrammatic form a complete receiver.

In the path of the light beam between a light source 130 and a receiving screen 146 are placed in succession three cells 131, 133 and 134. The

longer dimension of each cell lies in a plane which is parallel to the plane of the receiving screen, but whereas the longer dimension of the cell 131 is parallel to the length of the strips of the picture to be projected on the screen, the longer dimensions of the other cells are at right angles to this. To the crystal 132 of the first cell 131 is applied via terminals 138 a locally generated supersonic frequency which is modulated with the received picture currents, and by suitably choosing the length of the cell, the light transmitted through it is modulated in accordance with the light and shade values of one complete picture line so that this cell acts as a modulator cell. To the crystals 135 and 136 of the other cells 133, 134 are also applied supersonic frequencies which are modulated with impulses derived from generators 139, 140 to provide the desired wave slots. The frequency of the impulses applied to one cell differs from that of the frequencies applied to the other, these two frequencies being so chosen that each successive line of the picture is momentarily transmitted through two coincident wave slots and is projected on the screen, the point of coincidence moving step by step over the length of the cells so that each successive picture line is projected on to the screen immediately below the previous line.

It will be understood that the lenses previously described will have to be interposed in the path of the light beam in order to focus an image of one cell on the next and the slotted screens designed to obscure the central images must be inserted between the cells in the planes numbered 141, 142 and 143. Also a pair of cylindrical lenses 144, 145 are employed to focus an image of the cell 134 on the screen 146, the lens 144 increasing the size of this image in the plane at right angles to the plane of the paper; and the lens 145 reducing the size of the image in the plane of the paper.

Many modifications of the examples described above are possible. For example, in all the receivers described, the television signals which are received as modulations of a carrier wave have been obtained by demodulating the carrier wave, and are then utilized to modulate a locally generated high frequency oscillation before being applied to the crystals of the cells. Instead of this process it is possible to apply the modulated carrier directly to the crystals. In this case it is desirable to rectify the carrier without demodulation before applying it to the crystal, so that only the half waves of the carrier are applied to the crystal, in order to avoid losing the contrast present in the original picture. It is also possible to avoid the necessity of generating a separate carrier wave and utilizing a modulating circuit at the transmitter, by utilizing the high frequency oscillations applied to the crystal of the wave slot cell. This can be done by applying them to a second cell in the path of the light in such a way that standing waves are produced in this cell. In this case the current produced in the output circuit of the photo-cell will consist directly of a carrier wave modulated with the picture currents. If a so-called electron multiplier photo cell is employed, this modulated carrier current can be radiated directly from the output circuit of this cell.

Also, it is possible to obtain sharper impulses than by the method described with reference to Figs. 4 and 5 by allowing each received impulse to modulate momentarily the frequency as well as the amplitude of the high frequency oscillation,

the effect being analogous to that of the well known "zone plate".

I claim as my invention:

1. In a television system, apparatus for producing the high speed scanning component comprising a liquid adapted to be illuminated by a beam of light directed thereupon, wave generating means in contact with said liquid for producing therein trains of compressional waves of supersonic frequency travelling in a direction crossing that of a beam of light if directed upon said liquid, thereby resolving such a beam in a portion maintaining its original direction and a portion deviated from said direction, a shield member for selecting one of said portions, optical means for utilizing said selected portion to form an image of said waves on an elemental area of a surface to be scanned, an electrical arrangement for deriving synchronizing impulses of desired line scanning frequency, and means for utilizing said impulses to control the relation between the duration of illumination of said liquid and the active length of said trains of waves so that said image is periodically and momentarily produced at said line scanning frequency. 25

2. In a television system, apparatus for producing the high speed scanning component, comprising a liquid adapted to be illuminated by a beam of light directed upon said liquid wave generating means in contact with said liquid for producing therein discontinuous trains of compressional waves of supersonic frequency travelling in a direction crossing that of a light beam if directed upon said liquid, thereby resolving such a beam into a portion maintaining its original direction and a portion deviated from said direction, a shield member for selecting one of said portions, optical means for utilizing said selected portion to form an image of said waves on an elemental area of a surface to be scanned, an electrical arrangement for deriving synchronizing impulses of desired line scanning frequency, and means for utilizing said impulses to control the length of said trains of waves so that said image is periodically and momentarily produced at said line scanning frequency. 40

3. In a television system, apparatus for producing the high speed scanning component comprising means for developing an intermittent light beam, a liquid illuminated by said beam, wave generating means in contact with said liquid for producing in said liquid trains of compressional waves of supersonic frequency travelling in a direction crossing that of said beam, thereby resolving said beam into a portion maintaining its original direction and a portion deviated from said direction, a shield member for selecting one of said portions, a surface to be scanned, optical means for utilizing said selected portion to form an image of said waves on said surface, an electrical circuit for deriving synchronizing impulses of desired line scanning frequency, and means for utilizing said impulses to control the frequency of said intermittent light beam so that each elemental area of said surface is periodically and momentarily illuminated at said line scanning frequency. 65

4. In a television system, apparatus for producing the high speed scanning component comprising means for developing an intermittent light beam, a liquid illuminated by said beam, wave generating means in contact with said liquid for producing in said liquid discontinuous trains of compressional waves of supersonic frequency travelling in a direction crossing that of 70

- said beam, thereby resolving said beam into a portion maintaining its original direction and a portion deviated from said direction, a shield member for selecting one of said portions, a surface to be scanned, optical means for utilizing said selected portion to form an image of said waves on said surface, an electrical circuit for deriving synchronizing impulses of desired line scanning frequency, and means for utilizing said impulses to control the length of said trains of waves and the frequency of said intermittent light beam so that each elemental area of said surface is periodically and momentarily illuminated at said line scanning frequency.
- 5 15 5. A television receiver comprising a light source, a surface to be scanned, means for receiving television signals comprising picture signals and line synchronizing signals, two light control devices placed one after the other in the path of the light from said source to said screen, at least one of said devices comprising a transparent cell containing a liquid and having a piezo-electric crystal at one end thereof in contact with the liquid, means for applying said picture signals to one of said devices and said line synchronizing signals to the other of said devices, the signals applied to said cell being applied to the piezo-electric crystal in the form of modulations of a high frequency electrical oscillation whereby modulated travelling compressional waves are generated in the liquid of said cell and the light emerging from said cell consists of one part which maintains its original direction and a second part which is deviated from said direction, means for selecting one of said parts, an optical system for focussing an image of said waves on said surface, and a low speed scanning member interposed in the path of the light between the second of said devices and said surface.
- 20 30 40 6. A television receiver comprising a light source, a surface to be scanned, means for receiving television signals comprising picture signals and line synchronizing signals; two transparent cells placed in the path of the light from said source to said screen, each cell containing a liquid and having a piezo-electric crystal at one end thereof in contact with the liquid, means for applying said picture signals in the form of modulations of a high frequency electrical oscillation to one of said crystals to generate modulated travelling compressional waves in the liquid of the one cell, means for applying said line synchronizing impulses in the form of modulations of a high frequency electrical oscillation to the other of said crystals to generate modulated travelling compressional waves in the liquid of the other cell, a screen interposed between said cells, two slots in said screen, an optical system for focussing an image of said light source on said screen between said slots, a second screen between the second cell and said surface, three slots in said screen, an optical system for focussing an image of each of said slots of said first screen on said second screen, said images falling between the slots of said second screen, an optical system for focussing an image of said waves in the first cell on the liquid of said second cell, a further optical system for focussing an image of the waves of the second cell on said surface, and a low speed scanning member interposed in the path of the light between said second screen and said surface.
- 45 55 60 65 70 75 7. A television receiver according to claim 6 wherein said cells are parallel to one another and the image of the waves in the first cell moves in a direction opposite to the waves in the second cell.
8. A television receiver according to claim 6 wherein said two cells are replaced by a single cell having two piezo-electric crystals placed one above the other to generate two trains of travelling waves one above the other in the liquid of the cell, optical means being provided to reflect the light transmitted through one of said trains on to the other of said trains.
9. A television receiver comprising a plurality of light sources or the equivalent arranged side by side in a line, a surface to be scanned, means for receiving television signals comprising picture signals and line synchronizing signals, two light control devices placed one after the other in the path of the light from said sources to said surface, at least one of said devices comprising a transparent cell containing a liquid and having piezo-electric means in contact with said liquid, means for applying said picture signals to one of said devices and said line synchronizing signals to the other of said devices, the signals applied to said cell being applied to said piezo-electric means in the form of modulations of a high frequency electrical oscillation, said means being arranged to generate a plurality of trains of modulated travelling compressional waves, the number of said trains being equal to the number of said light sources, all of said trains travelling in the plane containing said light sources but in different directions, whereby each train is effective in influencing the light from one of said sources to produce one part of the light which maintains its original direction and a second part which is deviated from said direction, means for selecting one of said parts of the light from all of said sources, an optical system for focussing an image of said waves on said surface, and a low speed scanning member interposed in the path of the light between the second of said devices and said surface.
10. A television receiver comprising a light source means for developing from said source a light beam having a large aperture in one plane, a surface to be scanned, means for receiving television signals comprising picture signals, line synchronizing signals and picture synchronizing signals, two light control devices placed in the path of said light beam between said source and said surface, at least one of said devices comprising a transparent cell containing a liquid with a piezo-electric crystal at one end thereof in contact with the liquid, means for applying said picture signals to one of said devices and said line synchronizing signals to the other of said devices, the signals applied to said cell being applied to the crystal in the form of modulations of a high frequency electrical oscillation, whereby modulated travelling compressional waves are generated in the liquid in a plane at right angles to the plane containing the large aperture of said beam, the emergent light consisting of one part which maintains its original direction and second part which is deviated from said direction, means for selecting one of said parts, optical means for forming an image of said waves on said surface, a low speed scanning member controlled by said picture synchronizing signals interposed in the path of the light between said cell and said surface, the direction of scanning of said member being in a plane at right angles to the plane containing the direction of travel of said waves, and a stepped optical transforming device between said cell and said member for transforming the large aperture of said beam into the plane containing the direction of travel of said waves.
11. A television receiver according to claim 10

wherein said transforming device comprises a series of mirrors angularly displaced about an axis at right angles to the direction of travel of said waves, and a second series of mirrors angularly displaced about an axis at right angles to said first mentioned axis.

12. A television receiver according to claim 10 wherein said low speed scanning member comprises an oscillograph with a small mirror, said 10 oscillograph being actuated with currents having a saw-toothed wave form derived from a time-base circuit controlled by said picture synchronizing impulses.

13. A television transmitter for cinematograph 15 films comprising a light source, a film to be scanned, a transparent cell in the path of the light between said source and said film, a liquid in said cell, a piezo-electric crystal in contact with said liquid at one end of said cell, means for 20 generating electrical impulses of a desired frequency, means for generating high frequency electrical oscillations, means for modulating said oscillations with said impulses and applying the modulated oscillations to said crystal to produce 25 discontinuous groups of traversing compressional waves in said liquid whereby the light emerging from said cell comprises one part which maintains its original direction and a second part which is deviated from said direction, means for selecting 30 one of said parts, optical means for focussing an image of said waves on a long slot, the length of said slot being parallel to the traversing direction of said waves, means for focussing an image of said slot on said film, means for moving said 35 film in a direction at right angles to the length of said slot, means for shaping said impulses whereby the length of a wave group can be adjusted in relation to the distance between two successive wave groups, light sensitive means 40 situated behind said film, and a transmitting circuit connected to said light sensitive means.

14. A transmitter according to claim 13 wherein in the width of said slot is adjustable.

15. A television transmitter comprising means 45 for forming an image of an object to be televised on a screen, a long slot in said screen, a low speed scanning member for sweeping said image over said screen in a direction at right angles to the length of said slot, a light sensitive member, a transmitting circuit connected to said light sensitive member, and interposed in the path of said light from said screen to said light sensitive member in the order named a second screen, a first 50 optical system, a second optical system, a transparent cell containing a liquid and having piezo-electric means in contact with said liquid, and a third screen, said second screen having at least one slot, the length of said slots being at right angles to the length of the slot of said first screen, said first optical system forming an image of the slot of said first screen in said liquid, said second optical system forming images of the slots of said second screen on said third screen, said third screen being provided with a number of slots 55 which interleave with the images of the slots of said second screen, said piezo-electric means

being energized with a high frequency electrical oscillation modulated with impulses to produce in said liquid a number of trains of travelling compressional waves in the form of discontinuous groups, the number of trains being equal to the number of slots in said second screen, and the direction of travel of each of said trains lying in the plane containing the slot in said first screen and being different from one another.

16. A television receiver comprising a light 10 source, a surface to be scanned, and arranged in the path of the light between said source and said surface in the order named a first transparent cell containing a liquid and a piezo-electric crystal in contact with said liquid, and a second and third 15 transparent cells also containing a liquid with a piezo-electric crystal in contact therewith the axes of said second and third cells being parallel to one another and at right angles to the axis of said first cell, the crystal of said first cell being 20 energized with high frequency electrical oscillations modulated with picture signals derived from a transmitter, the crystals of said second and third cells being energized with high frequency electrical oscillations modulated with electrical impulses, the frequency of the impulses applied to 25 said second cell being different from those applied to said third cell, whereby the light emerging from each cell comprises one part which maintains its original direction and a second part 30 which is deviated from said direction, means being provided after each cell to select one of said parts, and further optical means being provided to focus an image of the liquid in said first cell on the liquid of said second cell, to focus an image 35 of the liquid of said second cell on the liquid of said third cell, and to focus an image of the liquid of said third cell on said surface to be scanned, the difference in the frequency between said electrical impulses being so chosen that an image of the 40 waves in said first cell is momentarily projected on said surface in successive positions one below the other to reconstitute the picture on said surface.

17. A television receiver comprising a surface to 45 be scanned means for producing an intermittent light beam, means for receiving television signals comprising picture signals and line synchronizing signals, means for utilizing the line synchronizing signals to control the frequency of the periods during which said intermittent light beam is active, a transparent cell placed in the path of said beam, a liquid in said cell, means for producing in said liquid high frequency travelling compressional waves modulated in amplitude in accordance with said picture signals whereby the light emerging from said cell consists of one part which maintains its original direction and a second part which is deviated from said direction, means for selecting one of said parts, an optical 50 system for utilizing said selected part to form an image of said waves on said surface, and a low speed scanning member interposed in the path of the light between said cell and said surface.

FRANZ VON OKOLICSANYI.
